UNITED STATES PATENT OFFICE.

CLYDE S. PELTON, OF CLEVELAND HEIGHTS, OHIO.

DESIGN FOR A VEHICLE-HEATER CASING.

57,148.

Specification for Design.

Patented Feb. 22, 1921.

Application filed May 8, 1920. Serial No. 379,993. Term of patent 14 years.

To all whom it may concern:

Be it known that I, CLYDE S. PELTON, a citizen of the United States, and a resident of Cleveland Heights, in the county of Cuyahoga and State of Ohio, have invented a new, original, and ornamental Design for a Vehicle-Heater Casing, of which the following is a specification, reference being had to

the accompanying drawing, forming part hereof, which represents a perspective view of a vehicle heater embodying my invention.

What I claim is:—

The ornamental design for a vehicle heater casing as shown.

CLYDE S. PELTON.
